UNITED STATES PATENT OFFICE.

FRANKLIN T. SPENCER, ARMEL JAMISON, AND CLAUDE G. JAMISON, OF PAINTED POST, NEW YORK.

HOT-AIR HEATER.

Application filed August 30, 1919. Serial No. 320,884.

To all whom it may concern:

Be it known that we, FRANKLIN T. SPENCER, ARMEL JAMISON, and CLAUDE G. JAMISON, citizens of the United States, residing at Painted Post, county of Steuben, and State of New York, have invented certain new and useful Improvements in Hot-Air Heaters, of which the following is a specification.

10 This invention relates to a hot air radiator, particularly designed for use in connection with gas, oil, stoves or "hot plates" and an object of the invention is to provide a radiator which is simple in construction, durable, and may be manufactured for a small cost, and is adapted to rest upon the stove for receiving the products of combustion rising from the burners thereof, and conserving them, permitting the heat therefrom

20 to radiate through the radiator structure for heating the surrounding atmosphere.

Another object of this invention is to provide a hot air radiator as specified, which is constructed of sheet metal, and has a baffle positioned therein, intermediate its top and bottom which baffle is either substantially conical or pyramidal in shape, having its under surface hollow, forming a pocket for receiving the products of combustion arising from the burners of the stove, and retaining them therein until they are completely consumed, and also permitting the utilization of the maximum heating effect of the fuel employed in connection with the stove.

Other objects of the invention will appear in the following detailed description taken in connection with the accompanying drawing, forming a part of this application, and in which drawing:

Figure 1 is a vertical section through the improved hot air radiator showing the same mounted upon a two burner gas stove.

Figure 2 is a top plan of the hot air radiator.

Figure 3 is a cross section taken on the line 3-3 of Figure 2.

Figure 4 is a top plan of a modified form of the hot air radiator, and

Figure 5 is a vertical section taken on the line 5-5 of Figure 4.

Referring more particularly to the drawing, the improved hot air radiator 10 is illustrated in Figure 1 of the drawing as mounted upon an ordinary two burner gas stove,

of the hot plate type. However, it is to be understood that the radiator may be used in connection with any approved type of gas or oil stove, without departing from the spirit of this invention. The radiator 10 comprises a body 11 constructed of sheet metal, and preferably rectangular in shape, depending upon the type of stove upon which it is to be used. The lower edges of the body 11 are inturned, as shown at 12, forming a support, which rests upon the top of the stove A, for supporting the body 11 over the burners B, of the stove A. The ends of the body 11 have handles 13 attached thereto to facilitate the placing of the radiator upon or the removing of it from a stove. A detachable cover 14 is mounted upon the upper end of the body 10, and has a depending annular flange which overlaps the upper edge of the body. The cover 14 is provided with a plurality of longitudinally and laterally spaced openings, 15, which are adapted to permit of the escape of products of combustion from the burners B of the stove therethrough. Suitable sheet metal brackets 17 are provided on the walls of said body 11. Each of said brackets comprises a portion lying parallel upon, and secured in any approved manner to the inner surface of the body 11; and a portion bent at an acute angle to said secured portion and spaced from the side of said body 11. A baffle 16 is secured to the under surface of the outwardly bent portion of the brackets 17. The baffle 16 is substantially pyramidal in shape, being constructed of sheet metal and providing an elongated pocket opening downwardly, which receives the products of combustion as they rise from the burners B and retains them therein until they are completely burned, thereby eliminating the passage of any odors from the stove A into the room or atmosphere surrounding the improved radiator structure, and also permitting of the utilization of the maximum heating effect of the fuel of the stove. It will be noted by particular reference to Figures 1 and 3 of the drawing, that the edges of the baffle 16 are spaced from the inner surface of the sides and ends of the body 11 thereby providing space to permit the heated air to rise in the radiator structure above the baffle member 16. Due to the fact that no obstructing parts are positioned in the heater above the baffle

plate; and likewise due to the upward tapering outer surface of the baffle 16 a space is provided above the baffle 16, which gradually increases in area upwardly from the lower marginal edges of said baffle 16, to provide a space for expanding heat and whereby a draft may quickly be effected through the radiator structure.

In Figures 4 and 5 of the drawing, a modified form of the hot air radiator structure is shown, this form being adapted for use upon stoves of the one burner type. In the modified form, the body 20 is cylindrical in shape and has its lower edge inturned, forming a horizontal flange 21 adapted to rest upon the surface of a stove, for supporting the radiator thereon. Handles 22 are attached to the outer surface of the cylindrical body 20 near its upper edge, and a cover 23 is mounted upon the top of the cylindrical body 20. This cover 23 is provided with a depending flange 24 which overlaps the upper edge of the body and is also provided with a plurality of perforations 25 extending therethrough to permit ventilation of the interior of the body 20 and also to permit the escape of hot air from within the body.

A conical baffle 26 is supported within the body 20, intermediate its ends, by suitable supporting brackets 27 which are similar in form, and attachment to the bracket 17. The conical baffle 26 is constructed of sheet metal and provides a pocket opening downwardly, for receiving therein the products of combustion as they rise from the burner of a stove

upon which the modified form of radiator is mounted. The lower outer edge of the baffle 26 is spaced from the inner surface of the cylindrical body 20 to permit the upward passage of heated air thereabout.

Changes in details may be made without departing from the spirit of this invention, but;

We claim:

In a hot air radiator, the combination with a range having burners, of a rectangular shaped body, a flat perforated cover detachably mounted thereon, the lower edges of said body being inturned to form a horizontal supporting flange, and providing an open space in the bottom thereof, for entrance thereof into the interior of the rectangular body, brackets secured to the inside of said body, each of said brackets having an outwardly extending portion, and a baffle disposed within said body and secured to the outwardly extending portion of said brackets in such manner that the edges of said baffle are spaced from the walls of said body to provide such space for passage of the heat, said baffle having its sides flat, and inclining toward each other, to provide an elongated pocket into which the heat passes prior to its entrance upwardly through the space and into the upper part of said body and outwardly through the perforations in said cover.
